UNITED STATES PATENT OFFICE

2,298,751

TELEPHONE SYSTEM

Thomas F. Crocker, Chicago, Ill., assignor to Associated Electric Laboratories, Inc., Chicago, Ill., a corporation of Delaware

Application September 6, 1940, Serial No. 355,630

20 Claims. (Cl. 179—27)

The present invention relates to telephone systems and, more particularly, to improved automatic switching apparatus of the character of that disclosed in U. S. Patent No. 2,167,710, Thomas F. Crocker, granted August 1, 1939, which apparatus is connected and arranged to handle switchboard traffic.

The telephone system disclosed in the above-mentioned Crocker patent comprises an automatic switchboard including a number of operator positions, including a group of inward or toll operator positions, a group of combined line and recording or C. L. R. operator positions and a group of delayed or point-to-point operator positions, at which the corresponding types of switchboard traffic are handled. More particularly, each operator position comprises a group of links individual thereto and apparatus for selectively controlling the links in the associated group; whereby calls may be answered, extended; supervised and released by way of the links in the associated group and the various control functions may be performed in conjunction with the calls by way of the links in the associated group.

Also, the system comprises distributor apparatus which is governed in response to the manual preparation for use of an idle link at a given operator position for selecting the given operator position to answer the next incoming call and which is then governed in response to the arrival of a call for routing the call to the given operator position to be answered.

While a telephone system of the type described is entirely satisfactory in operation and extremely efficient when the switchboard is relatively large, it requires a larger number of operator positions at the switchboard and more attention of the operators thereto than is desirable, particularly when the switchboard is relatively small.

Accordingly, it is an object of the present invention to provide in a telephone system comprising a switchboard including a number of universal operator positions, each operator position being adapted to handle the different types of switchboard traffic, an improved distributor arrangement for routing the different types of calls to the various operator positions at the switchboard to be answered.

Another object of the invention is to provide in a telephone system comprising a switchboard including a number of operator positions, an improved distributor arrangement for automatically routing calls to idle ones of the operator posi-

tions at the switchboard, which requires no special conditioning of the operator positions by the operators thereto.

Another object of the invention is to provide in a telephone system comprising an operator position including a number of links, an improved distributor arrangement for routing calls over idle ones of the links to the operator position, which requires no special conditioning of the links by the operator at the operator position.

A further object of the invention is to provide in a telephone system comprising an operator position including a number of links, an improved arrangement which may be selectively controlled both automatically, by distributor equipment, and manually, by the operator at the operator position, for routing calls over idle ones of the links to the operator position.

A still further object of the invention is to provide in a telephone system comprising an operator position including a plurality of links, an improved arrangement for extending calls by way of the links to the operator position and for extending calls by way of the links from the operator position and for controlling the supervision at the operator position of calls extended by way of the links.

The invention is illustrated as being embodied in a telephone system comprising a central office terminating various groups of trunk and toll lines and provided with a switchboard including a number of operator positions. Also, the central office comprises automatic switching apparatus including a number of groups of links individually associated with the operator positions at the switchboard.

In accordance with one feature of the invention, the telephone system comprises a distributor arrangement including a position distributor operative to select the ones of the groups of links associated with idle ones of the operator positions in a predetermined order, and a plurality of link distributors individually corresponding to the groups of links and respectively operative to select idle ones of the links in the associated group of links in a predetermined order. Also, the distributor arrangement comprises means responsive to the presence of a call on any one of the lines for connecting a selected one of the links in a selected one of the groups of links to the associated one of the operator positions and to the calling line, thereby to extend the call on the calling line to the one operator position to be answered. Further, the system comprises means

controllable from the one operator position for connecting the one link to a called one of the lines, thereby to complete a connection between the calling line and the called line, means controlled when the one link is connected to either the calling line or the called line for rendering busy the one link, means for disconnecting the one link from the operator position, and means controlled when a busy one of the links is connected to the operator position for rendering busy the operator position.

In accordance with another feature of the invention, the system comprises additional means controllable from the one operator position for connecting an idle one of the links in the associated group to the one operator position and to a calling one of the lines, thereby to extend the call on the calling line to the one operator position to be answered, whereby the call on a calling line may be routed to the one operator position, either under the automatic control of the distributor arrangement or under the manual control of the operator at the one operator position.

In accordance with a further feature of the invention, each link comprises an answer switch having access to calling lines and a call switch having access to called lines; and each operator position comprises position apparatus selectively operative to answer, to extend, to supervise and to release, by way of the links in the associated group, the various calls, and to perform, in conjunction with the calls, by way of the links in the associated group, various control and supervisory functions.

Further features of the invention pertain to the particular arrangement of the circuit elements of the system, whereby the above-outlined and additional operating features are attained.

The novel features believed to be characteristic of the invention are set forth with particularity in the appended claims. The invention, both as to its organization and method of operation, together with further objects and advantages thereof, will best be understood by reference to the following specification taken in connection with the accompanying drawings in which Figure 1 illustrates the general arrangement of a telephone system embodying the present invention; Figs. 2 to 9, inclusive, taken together, illustrate the details of a system having incorporated therein the features of the invention, as briefly outlined above; and Fig. 10 illustrates the mode of combining Figs. 2 to 9, inclusive, to form a unified system.

Description of the apparatus incorporated in the telephone system

Referring now more particularly to Fig. 1 of the drawings, the telephone system there illustrated comprises a central office CO and two distant exchanges DE-1 and DE-2. The central office CO and each of the distant exchanges DE-1 and DE-2 serve a number of local subscriber substations, the central office CO serving the local subscriber substations T-1 and T-2 respectively associated with the subscriber lines 201 and 406. The central office CO and the distant exchange DE-1 are interconnected by a group of two-way toll lines, including the toll line indicated at TL-1; similarly, the central office CO and the distant exchange DE-2 are interconnected by a group of two-way toll lines, including the toll line indicated at TL-2. It is noted that the toll line TL-1 extending between the central office CO and the distant exchange 75

DE-1 terminates at an operator position 210 in the distant exchange DE-1; similarly, the toll line TL-2 extending between the central office CO and the distant exchange DE-2 terminates at an operator position 410 in the distant exchange DE-2. Each of the toll lines extending to the central office CO terminates in a toll line circuit, the toll line TL-1 terminating in the toll line circuit TLC-1.

The central office CO is of the automatic type, while the distant exchanges DE-1 and DE-2 may be of any suitable type. Accordingly, the central office CO is provided with a local switch train, including the portions LST-1 and LST-2, each comprising a plurality of groups of finders, selectors and connectors of the Strowger type arranged in the usual manner in order to set up the various connections between the local subscriber substations in the central office CO.

Also, a group of combined line and recording or C. L. R. trunks, including the C. L. R. trunk 205, is provided in the central office CO, which trunks are accessible to the local switch train LST-1. Furthermore, a C. L. R. trunk circuit is individually associated with each C. L. R. trunk, the C. L. R. trunk circuit CLR-1 being individually associated with the C. L. R. trunk 205.

Further, the central office CO is provided with a toll switch train comprising a plurality of groups of finder-selector links, one of the groups including the link illustrated which comprises the finder F-1 and the toll first selector TFS-1; a group of toll delayed selectors, including the toll delayed selector TDS-1; and a group of toll switches indicated at TST. Preferably, the switches are of the Strowger type and are connected and arranged in a manner more fully described subsequently.

An automatic dial switchboard is arranged in the central office CO and comprises a number of operator positions, each operator position having a group of finder-selector links individually associated therewith. For example, the finder-selector link illustrated is included in the group of links individually associated with the first operator position OP-1 at the switchboard. Each of the finders of the finder-selector links has access to each of the C. L. R. trunks in the central office CO, to each of the toll lines extending between the central office CO and the distant exchanges DE-1 and DE-2, to each toll delayed selector and to a group of interposition transfer trunks individual to the associated operator position. For example, the group of interposition 50

55 transfer trunks, including the interposition transfer trunk 401, is individual to the first operator position OP-1 and is utilized for the purpose of transferring calls from other operator positions at the switchboard to the first operator position OP-1 thereat. Also, it is noted that an interposition transfer circuit is individually associated with each interposition transfer trunk, the interposition transfer circuit ITC-1 being individually associated with the interposition transfer trunk 401. More specifically, the finder F-1 of the finder-selector link illustrated has access to the C. L. R. trunk 205 by way of the trunk line 203, to the toll line TL-1 by way of the trunk line 202, to the toll delayed selector TDS-1 by way of the trunk line 206, and to the interposition transfer trunk 401 by way of the trunk line 204. Furthermore, the finder F-1 is accessible to the trunk circuit at the first operator position OP-1 by way of the cable #1.

Also, each toll first selector and each toll de-

layered selector have access to each of the interposition transfer trunks, to the toll switch train TST and to the local switch train LST-2. More specifically, the toll first selector TFS-1 and the toll delayed selector TDS-1 each have access to the interposition transfer trunk 401 directly, to the toll switch train TST by way of the trunk line 402, and to the local switch train LST-2 by way of the trunk line 403. Also, it is noted that the toll switch train TST has access to each of the toll lines extending between the central office CO and the distant exchanges DE-1 and DE-2. For example, the toll switch train TST has direct access to the toll line TL-2 extending between the central office CO and the distant exchange DE-2.

Preferably, each of the operator positions, including the first operator position OP-1 at the switchboard in the central office CO, is of the universal type, thereby making it possible to render toll, C. L. R. and point-to-point service at each operator position. Also, the central office CO comprises a position distributor PD and a group of link distributors individually corresponding to the operator positions at the switchboard. For example, the group of link distributors includes the first position link distributor LD-1 individually associated with the first operator position OP-1 at the switchboard. The position distributor PD is so connected and arranged that idle ones of the operator positions at the switchboard are selected in a predetermined order to answer calls; while each link distributor is so connected and arranged that idle ones of the finder-selector links at the associated operator position are selected in a predetermined order for use in routing calls to be answered.

Also, individually associated with each operator position is a sequence control circuit SCC which has access to two individually associated sender links SL-1 and SL-2. Furthermore, at each operator position, there is provided a group of operator digit keys DK individual thereto which is associated with each of the sender links SL-1 and SL-2. Finally, a group of register senders, including the register sender RS, is commonly associated with the switchboard. Each of the sender links comprises a link finder and a sender selector, the sender links SL-1 and SL-2 respectively comprising the link finders LF-1 and LF-2 and the sender selectors SS-1 and SS-2. Each of the link finders has access to the trunk circuit at the associated operator position by way of cable #3 and to each finder-selector link at the associated operator position by way of cable #2; similarly, each of the sender selectors has access to each of the register senders by way of cable #4.

Preferably, each of the toll line circuits, such as TLC-1, shown in Fig. 2, is identical to that disclosed in Fig. 2 of the previously mentioned Crocker patent; each of the combined line and recording trunk circuits, such as CLR-1, shown in Fig. 2, is identical to that disclosed in Fig. 3 of the previously mentioned Crocker patent; and each of the interposition transfer circuits, such as ITC-1, shown in Fig. 2, is identical to that disclosed in Fig. 5 of the previously mentioned Crocker patent.

The position distributor PD comprises, as best shown in Fig. 8, a start relay 1210, a reset relay 1220, a hold relay 1225, three select relays 1230, 1235 and 1240, respectively corresponding to the first, second and third operator positions at the switchboard, and a control network.

Preferably, each of the link distributors is identical to the first position link distributor LD-1 which comprises, as best shown in Fig. 8, a reset relay 1245, a hold relay 1250, three select relays 1255, 1260 and 1265 individually corresponding to the first, second and third finder-selector links associated with the first operator position OP-1 at the switchboard, and a control network.

10 The sequence control circuit SCC, the sender links SL-1 and SL-2 and the operator digit keys DK, shown in Fig. 7, are identical to those disclosed in Figs. 15 and 16 of the previously mentioned Crocker patent; while the register sender RS, shown in Fig. 7, is identical to that disclosed in Figs. 17 to 21, inclusive, of the previously mentioned Crocker patent.

Preferably, each of the operator positions at the switchboard is identical to the first operator position OP-1, shown in Figs. 5, 6 and 9, which operator position is substantially identical to that disclosed in Figs. 11, 13 and 14 of the previously mentioned Crocker patent. More particularly, the first operator position OP-1 comprises position telephone equipment, a group of position relays and a position key set. More particularly, the position key set comprises a delay call key K-3, a cut-off answer key K-5, a transfer answer key K-6, a ring answer key K-7, a release answer key K-8, a dial answer key K-9, an emergency start key K-10, a release answer and call key K-11, a release call key K-12, a ring call key K-13, a transfer call key K-14, a cut-off call key K-15, a without key K-16, a position group key K-17 and a busy key K-18; while the position telephone equipment comprises a headset, a talking repeater TR and a monitoring repeater MR. The group of position relays comprises a transmitter supply relay 1110, a monitor relay 1120, a talk relay 1130, a call signal relay 1140, two signal interrupter relays 1150 and 1160, a start relay 1170, a split answer relay 1310, a split call relay 1320, a transfer relay 1330, an answer pilot relay 1340, a call pilot relay 1350, an error relay 1360, two supervisory relays 1380 and 1370, a call relay 1380 and a cut-through relay 1390. Certain of the relays mentioned are connected and arranged for the purpose of controlling the association of the headset at the first operator position OP-1 with the trunk circuit therat; while other of the relays mentioned are so connected and arranged that they control the transmission of tone to the receiver of the headset at the first operator position OP-1 when an incoming call is routed thereto. Finally, the remainder of the relays mentioned are so connected and arranged that various types of toll and trunk calls may be initiated, answered, released and supervised from the first operator position OP-1, in a manner more fully described subsequently.

40 As previously noted, a group of finder-selector links is individually associated with each operator position, the finder-selector link illustrated comprising the finder F-1, shown in Fig. 3, and the toll first selector TFS-1, shown in Fig. 4, being included in the group of finder-selector links individually associated with the first operator position OP-1. Preferably, each of the finder-selector links is identical to the finder-selector link illustrated, the finder F-1 of this link being operatively associated with cable #1 extending to the trunk circuit at the first operator position OP-1.

45 50 55 60 65 70 75 The finder F-1, shown in Fig. 3, corresponds

to that shown in Fig. 6 of the previously mentioned Crocker patent and comprises a switching mechanism of the 200-point Strowger type including a wiper carriage capable of both vertical and rotary movements, a vertical magnet for moving the wiper carriage in the vertical direction, a rotary magnet for moving the wiper carriage in the rotary direction and a release magnet for releasing the wiper carriage and for causing it to be returned to its normal position. Also, the finder F-1 comprises a group of relays, including two electropolarized relays 610 and 620, a change-over relay 630, a step relay 640, a supervisory relay 650, a start relay 660, a connect relay 670, a cut-through relay 680, an automatic start relay 690 and an automatic answer relay 695. Moreover, the finder F-1 has individually associated therewith at the first operator position OP-1 a link listening or talk key K-1 and a monitoring key K-2 which are operative to associate the finder F-1 with cable #1 extending to the first operator position OP-1. Finally, a number of lamps, including a call lamp 691, an answer lamp 602 and a link-busy lamp 603 are associated with the finder F-1 for supervisory purposes.

The toll first selector TFS-1, shown in Fig. 4, is identical to that disclosed in Fig. 7 of the previously mentioned Crocker patent. Preferably, each of the toll delayed selectors is identical to the toll delayed selector TDS-1, shown in Fig. 4, which is in turn identical to the toll first selector TFS-1, shown in Fig. 4. Also, the apparatus at the operator positions 210 and 410, respectively shown in Fig. 2 and Fig. 4 and respectively disposed in the distant exchanges DE-1 and DE-2, is entirely conventional; and each subscriber substation in the central office CO is provided with conventional automatic subscriber substation equipment.

A better understanding of the connection and arrangement of the apparatus incorporated in the telephone system will be facilitated from a consideration of the detailed operation of the various pieces of apparatus incident to the handling of the various toll and trunk calls at the switchboard, as will appear hereinafter.

Operations of the position distributor and the link distributors

Considering now the operation of the position distributor PD, when the first operator position OP-1 at the switchboard is idle, this position being idle when the operator thereat is not engaged in answering or extending a call and when there are idle links in the associated group of links, no ground potential appears upon the guard conductor 1270 of the first operator position OP-1 in cable #1. On the other hand, when the first operator position OP-1 at the switchboard is busy, due either to the fact that the operator thereat is engaged in answering or extending a call, or the fact that all of the links in the associated group are busy, ground potential appears upon the guard conductor 1270 of the first operator position OP-1 in cable #1. Similarly, ground potential appears upon the guard conductors 1272 and 1274, respectively, when the intermediate and last operator positions at the switchboard are busy. Thus, when one of the operator positions is idle, one of the select relays 1230, 1235 or 1240, together with the hold relay 1225, are operated.

Assuming that the first operator position OP-1 is idle and that the position distributor

PD has operated to select the first operator position OP-1 at this time, a circuit is completed for energizing in series the winding of the hold relay 1225 and the upper winding of the select relay 1230. The last-mentioned circuit extends from ground by way of the contacts 1221, the winding of the hold relay 1225, the contacts 1236 and 1232 and the upper winding of the select relay 1230 to battery. The operated hold relay 1225 retains interrupted, at the contacts 1226, a point in an obvious circuit for energizing the lower winding of the select relay 1230. The operated select relay 1230 retains completed, at the contacts 1232, the previously traced holding circuit for energizing the upper winding thereof in series with the winding of the hold relay 1225. Also, the operated select relay 1230 retains interrupted, at the contacts 1231, a point in a holding circuit substantially identical to that previously traced for energizing the upper winding of the select relay 1240 in series with the winding of the hold relay 1225, and retains prepared, at the contacts 1233, a circuit traced hereinafter for energizing the lower winding of the select relay 1235. Finally, the operated select relay 1230 retains completed, at the contacts 1234, an obvious connection between the common link start conductor 1290 and the individual link start conductor 1271, the individual link start conductor 1271 extending to the first position link distributor LD-1.

When the first operator position OP-1 is rendered busy, ground potential is applied to the guard conductor 1270 thereof in cable #1, thereby to complete an obvious circuit for energizing the lower winding of the select relay 1235 in order to cause the latter relay to operate. Upon operating, the select relay 1235 completes, at the contacts 1237, an obvious holding circuit substantially identical to that previously traced for energizing the upper winding thereof in series with the winding of the hold relay 1225, interrupts, at the contacts 1236, the previously traced holding circuit for energizing the upper winding of the select relay 1230 in series with the winding of the hold relay 1225 in order to cause the select relay 1230 to restore, prepares, at the contacts 1238, an obvious circuit for energizing the lower winding of the select relay 1240, and completes, at the contacts 1239, an obvious connection between the common link start conductor 1290 and the individual link start conductor 1273, the individual link start conductor 1273 extending to the intermediate position link distributor, not shown.

In the event the intermediate operator position is idle, further operation of the position distributor PD is arrested, whereupon the intermediate operator position is selected at this time. On the other hand, in the event the intermediate operator position is busy at this time, ground potential appears upon the guard conductor 1272 thereof, thereby to complete the previously mentioned circuit for energizing the lower winding of the select relay 1240, in order to cause the latter relay to operate; whereupon the last operator position is selected in the event it is idle at this time, in the manner previously explained.

In the event the last operator position is busy at this time, ground potential appears upon the guard conductor 1274 thereof, thereby to complete an obvious circuit for energizing the winding of the reset relay 1220. When thus energized, the reset relay 1220 operates to interrupt, at the contacts 1221, the previously mentioned

holding circuit for energizing the upper winding of the select relay 1240 in series with the winding of the hold relay 1225, thereby to cause the select relay 1240 to restore immediately and the hold relay 1225 to restore shortly thereafter, the hold relay 1225 being of the slow-to-release type. Upon restoring, the select relay 1240 interrupts, at the contacts 1243, the previously mentioned circuit for energizing the winding of the reset relay 1220, thereby to cause the latter relay to restore shortly thereafter, the reset relay 1220 being of the slow-to-release type. Upon restoring, the reset relay 1220 completes, at the contacts 1221, an obvious circuit for energizing the lower winding of the select relay 1230, thereby to cause the latter relay to operate and complete, at the contacts 1232, the previously traced holding circuit for energizing the upper winding thereof in series with the winding of the hold relay 1225. When thus energized, the hold relay 1225 operates to interrupt, at the contacts 1226, the previously mentioned circuit for energizing the lower winding of the select relay 1230.

In view of the above description of the mode of operation of the position distributor PD, it will be understood that idle ones of the operator positions at the switchboard are selected thereby in a predetermined order.

Considering now the operation of the first position link distributor LD-1, when the first link, the link illustrated, at the first operator position OP-1 is idle, no ground potential appears upon the guard conductor 1281 of the first link in cable #1. On the other hand, when the first link at the first operator position OP-1 is busy, ground potential appears upon the guard conductor 1281 of the first link in cable #1. Similarly, ground potential appears upon the guard conductors 1283 and 1285, respectively, when the intermediate and last links at the first operator position OP-1 are busy. Thus, when one of the links at the first operator position OP-1 is idle, one of the select relays 1255, 1260 and 1265, together with the hold relay 1250, are operated.

Assuming that the first link at the first operator position OP-1 is idle and that the first position link distributor LD-1 has operated to select the first link at the first operator position OP-1 at this time, a circuit is completed for energizing in series the winding of the hold relay 1250 and the upper winding of the select relay 1255. The last-mentioned circuit extends from ground by way of the contacts 1241, the winding of the hold relay 1250, the contacts 1262 and 1258 and the upper winding of the select relay 1255 to battery. The operated hold relay 1250 retains interrupted, at the contacts 1251, a point in an obvious circuit for energizing the lower winding of the select relay 1255. The operated select relay 1255 retains completed, at the contacts 1258, the previously traced holding circuit for energizing the upper winding thereof in series with the winding of the hold relay 1250. Also, the operated select relay 1255 retains interrupted, at the contacts 1257, a point in a holding circuit substantially identical to that previously traced for energizing the upper winding of the select relay 1265 in series with the winding of the hold relay 1250, and retains prepared, at the contacts 1259, a circuit traced hereinafter for energizing the lower winding of the select relay 1260. Finally, the operated select relay 1255 retains completed, at the contacts 1256, an obvious connection between the individual link start conductor 1271 extending between the position dis-

tributor PD and the first position link distributor LD-1 and the start conductor 1282 extending to the first link at the first operator position OP-1.

- 5 When the first link at the first operator position OP-1 is rendered busy, ground potential is applied to the guard conductor 1281 thereof in cable #1, thereby to complete an obvious circuit for energizing the lower winding of the select relay 1260 in order to cause the latter relay to operate. Upon operating, the select relay 1260 completes, at the contacts 1263, an obvious holding circuit substantially identical to that previously traced for energizing the upper winding thereof in series with the winding of the hold relay 1250, interrupts, at the contacts 1262, the previously traced holding circuit for energizing the upper winding of the select relay 1255 in series with the winding of the hold relay 1250 in order to cause the select relay 1255 to restore, prepares, at the contacts 1264, an obvious circuit for energizing the lower winding of the select relay 1265, and completes, at the contacts 1261, an obvious connection between the individual link start conductor 1271, extending between the position distributor PD and the first position link distributor LD-1, and the start conductor 1284 extending to the intermediate link at the first operator position OP-1.
- 10 In the event the intermediate link at the first operator position OP-1 is idle, further operation of the first position link distributor LD-1 is arrested, whereupon the intermediate link at the first operator position OP-1 is selected at this time. On the other hand, in the event the intermediate link at the first operator position OP-1 is busy at this time, ground potential appears upon the guard conductor 1283 thereof, thereby to complete the previously mentioned circuit for energizing the lower winding of the select relay 1265, in order to cause the latter relay to operate; whereupon the last link at the first operator position OP-1 is selected in the event it is idle at this time, in the manner previously explained.
- 15 In the event the last link at the first operator position OP-1 is busy at this time, ground potential appears upon the guard conductor 1285 thereof, thereby to complete an obvious circuit for energizing the winding of the reset relay 1245. When thus energized, the reset relay 1245 operates to interrupt, at the contacts 1247, the previously mentioned holding circuit for energizing the upper winding of the select relay 1265 in series with the winding of the hold relay 1250, thereby to cause the select relay 1265 to restore immediately and the hold relay 1250 to restore shortly thereafter, the hold relay 1250 being of the slow-to-release type. Upon restoring, the select relay 1265 interrupts, at the contacts 1267, the previously mentioned circuit for energizing the winding of the reset relay 1245, thereby to cause the latter relay to restore shortly thereafter, the reset relay 1245 being of the slow-to-release type. Upon restoring, the reset relay 1245 completes, at the contacts 1247, an obvious circuit for energizing the lower winding of the select relay 1255, thereby to cause the latter relay to operate and complete, at the contacts 1258, the previously traced holding circuit for energizing the upper winding thereof in series with the winding of the hold relay 1250. When thus energized, the hold relay 1250 operates to interrupt, at the contacts 1251, the previously mentioned circuit for energizing the lower winding of the select relay 1255.

In view of the above description of the mode of operation of the first position link distributor LD-1, it will be understood that idle ones of the links at the first operator position OP-1 are selected thereby in a predetermined order. Furthermore, it will be understood that the intermediate position link distributor and the last position link distributor operate in a manner identical to that of the first position link distributor LD-1, described above.

Also, it is noted that when the first operator position at the switchboard is busy, due either to the fact that the operator thereat is engaged in answering or extending a call or the fact that all of the links in the associated group are busy, the application of ground potential to the guard conductor 1270 thereof in cable #1 completes an obvious circuit for energizing the winding of the reset relay 1245 in the first position link distributor LD-1. When thus energized, the reset relay 1245 operates to reset the first position link distributor LD-1, in the manner previously explained. Also, the reset relay 1245 prepares, at the contacts 1246, a point in a chain circuit for energizing the winding of the reset relay 1220 in the position distributor PD. The above-mentioned chain circuit is completed when the reset relay in each of the link distributors is operated, thereby to cause operation of the reset relay 1220 in the position distributor PD, in the manner previously explained. Thus, it will be understood that, when all of the links in the group associated with a given operator position are busy, the operation of the associated link distributor is arrested; and that when all of the operator positions at the switchboard are busy, the operation of the position distributor PD is arrested.

Extension of a call from a local subscriber substation in the central office to the switchboard therein

In order to establish a connection between a local subscriber substation in the central office CO, such as the subscriber substation T-1, and the switchboard, the subscriber at the subscriber substation T-1 first initiates a call in the regular manner, thereby to cause the local switch train LST-1 to seize the subscriber line 201 extending to the subscriber substation T-1, in a conventional manner. The subscriber at the subscriber substation T-1 then dials a predetermined digit or digits into the local switch train LST-1, thereby to cause the local switch train LST-1 to operate and seize an idle C. L. R. trunk, such as the C. L. R. trunk 205. When the C. L. R. trunk 205 is thus seized, the combined line and recording trunk circuit CLR-1 individually associated therewith operates, thereby to cause ground potential to be applied to the start conductor 313 and to cause the trunk line 203 extending thereto to be marked for selection. The application of ground potential to the start conductor 313 completes, by way of a corresponding one of the start leads 1200, an obvious circuit for energizing the winding of the start relay 1210 in the position distributor PD. Assuming that the position distributor PD has preselected the first operator position OP-1 at the switchboard and that the first position link distributor LD-1 has preselected the first link at the first operator position OP-1, the call from the subscriber substation T-1 is routed to the first operator position OP-1 at the switchboard by way of the first link in the associated group. More particularly, upon operating, the start relay 1210 completes,

at the contacts 1212, a path for applying ground potential to the start conductor 1282 of the first link at the first operator position OP-1 at the switchboard in cable #1, this path extending from ground by way of the contacts 1212, the common link start conductor 1290, the contacts 1234, the individual link start conductor 1271, and the contacts 1256 to the start conductor 1282 of the first link at the first operator position OP-1 at the switchboard in cable #1. Also, the start relay 1210 completes, at the contacts 1211, obvious multiple circuits for illuminating the answering lamps 1204, etc., at the various operator positions at the switchboard, thereby to indicate the presence of an unanswered call to the operators thereat.

The application of ground potential to the start conductor 1282 in cable #1 completes a circuit for energizing the winding of the automatic start relay 600 in the finder F-1, this circuit extending from the grounded start conductor 1282 by way of the contacts 627 and 617 and the winding of the automatic start relay 600 to battery. When thus energized, the automatic start relay 600 operates to complete, at the contacts 602, a circuit for energizing the lower winding of the connect relay 670, this circuit extending from ground by way of the contacts 1133, the test conductor 604 in cable #1, the contacts 602 and the lower winding of the connect relay 670 to battery. When thus energized, the connect relay 670 operates to complete, at the contacts 679, a holding circuit for energizing the upper winding thereof in series with the winding of the talk relay 1130, this circuit extending from ground by way of the winding of the talk relay 1130, the hold conductor 605 in cable #1, the contacts 601 and 679 and the upper winding of the connect relay 670 to battery. When this holding circuit is completed the talk relay 1130 operates shortly thereafter, this relay being of the slow-to-operate type, to complete, at the armatures 1131 and 1132 and the front contacts associated therewith, an obvious connection between the tip conductor 1180 and the ring conductor 1181 of the trunk circuit at the first operator position OP-1 and the talking repeater TR thereat, thereby operatively to associate the operator headset at the first operator position OP-1 with the tip conductor 1180 and the ring conductor 1181 of the trunk circuit thereat. Also, the talk relay 1130 interrupts, at the contacts 1133, the previously traced circuit for energizing the lower winding of the connect relay 670, thereby positively to prevent the operation of the connect relay in the finder of any other link in the associated group at this time. Further, the talk relay 1130 completes, at the contacts 1135, a circuit for energizing the winding of the start relay 1170, this circuit extending from ground by way of the contacts 1135, the conductor 1185, the contacts 1351 and 1343, the conductor 1184, the winding of the start relay 1170 and the contacts of the delay call key K-3 to battery. When thus energized, the start relay 1170 operates shortly thereafter, this relay being of the slow-to-operate type, to prepare, at the contacts 1171, a point in a circuit traced hereinafter for energizing the winding of the call signal relay 1140.

Also, upon operating, the automatic start relay 600 completes, at the contacts 604, a circuit for energizing the upper winding of the automatic answer relay 605, this circuit extending from ground by way of the contacts 604, the upper winding of the automatic start relay 605 and the resistor R1 to battery. When thus energized, the

automatic answer relay 605 operates to complete, at the contacts 606, an obvious holding circuit for energizing the lower winding thereof, including the resistor R7. Also, the automatic answer relay 605 completes, at the contacts 607, an obvious circuit for illuminating intermittently the link-busy lamp 603 by way of the interrupter 609, thereby to cause the link-busy lamp 603 to flash. The flashing link-busy lamp 603 indicates to the operator at the first operator position OP-1 that a call is being extended to the first operator position OP-1 by the position distributor PD and the first position link distributor LD-1 by way of the first link in the associated group.

Also, upon operating, the connect relay 610 completes, at the contacts 672 and 674, an obvious connection between the finder F-1 and the ring answer conductor 654 and the tip answer conductor 653, respectively, in cable #1, the ring answer conductor 654 and the tip answer conductor 653 being respectively connected by the armatures 1312 and 1311 and the back contacts associated therewith to the ring conductor 1181 and the tip conductor 1180, respectively, of the trunk circuit at the first operator position OP-1. Accordingly, at this time, the operator headset at the first operator position OP-1 is operatively connected to the finder F-1. Also, the connect relay 610 interrupts, at the armature 675 and the back contact associated therewith, an obvious path for applying ground potential to the marking conductor 1557 in the cable #2, thereby to mark the first link at the first operator position OP-1 as a calling link to the link finder of the selected sender link, for a purpose more fully explained hereinafter.

Also, upon operating, the automatic start relay 600 completes, at the contacts 603, an obvious circuit for energizing the winding of the start relay 660, thereby to cause the latter relay to operate. Upon operating, the start relay 660 interrupts, at the contacts 661, a point in an obvious circuit for energizing the release magnet of the finder F-1, and completes, at the contacts 663, obvious multiple circuits for energizing the lower windings of the electropolarized relays 610 and 620. Also, the start relay 660 completes, at the contacts 663, a circuit for energizing the vertical magnet, this circuit extending from ground by way of the contacts 663, 625, 615 and 641, the armature 635 and the back contact associated therewith and the vertical magnet to battery. When thus energized, the vertical magnet operates to drive the wiper carriage of the finder F-1 one step in the vertical direction, and to complete, at the contacts 698, an obvious circuit for energizing the winding of the step relay 640. When thus energized, the step relay 640 operates to interrupt, at the contacts 641, the previously traced circuit for energizing the vertical magnet, thereby to cause the vertical magnet to restore. Accordingly, the step relay 640 and the vertical magnet interact in the manner described above, thereby to cause the wiper carriage of the finder F-1 to be driven step by step in the vertical direction until the control wiper 617 engages the contact in the associated contact bank terminating the start lead 1200 marked by the application of ground potential to the start conductor 313 in the combined line and recording trunk circuit CLR-1.

When the wiper carriage of the finder F-1 is operated to the level terminating the trunk line 203 extending to the combined line and recording trunk circuit CLR-1, the control wiper 617 en-

gages a contact in the associated contact bank having ground potential thereon, as previously noted, whereupon an obvious circuit is completed for energizing the lower winding of the change-over relay 630 in series with the winding of the step relay 640 when the vertical magnet restores. Shortly after the change-over relay 630 is thus energized this relay operates, the change-over relay 630 being of the slow-to-operate type, to complete, at the contacts 632, a holding circuit for energizing the upper winding thereof, this circuit extending from ground by way of the upper winding of the change-over relay 630, the off-normal springs 645, the post normal springs 646, the contacts 632 and the resistor R4 to battery. Also, the change-over relay 630 interrupts at the armature 635 and the back contact associated therewith, the previously traced circuit for energizing the vertical magnet, and completes, at the armature 635 and the front contact associated therewith, a circuit substantially identical to that previously traced for energizing the rotary magnet, whereupon the rotary magnet and the step relay 640 interact in a manner similar to that previously explained, thereby to drive the wiper carriage of the finder F-1 step by step in the rotary direction.

When the wiper set 618 carried by the wiper carriage of the finder F-1 engages the contact in the associated contact bank terminating the trunk line 203 extending to the combined line and recording trunk circuit CLR-1, a circuit is completed for energizing the upper winding of one of the electropolarized relays 610 or 620, depending upon which one hundred line group includes the trunk line 203, in a well-known manner. Assuming that the trunk line 203 is included in the first one hundred line group, a circuit is completed for energizing the upper winding of the electropolarized relay 610 in series with the lower winding of the supervisory relay 650, this circuit extending from ground by way of the contacts 634, the lower winding of the supervisory relay 650, the armature 623 and the back contact associated therewith, the upper winding of the electropolarized relay 610 and the control wiper C1 of the wiper set 618 carried by the wiper carriage of the finder F-1 to the control conductor of the trunk line 203, battery potential being present upon the control conductor of the trunk line 203. When thus energized, the electropolarized relay 610 operates exceedingly fast due to the previously completed circuit for energizing the lower winding thereof to complete, at the contacts 614, an obvious holding circuit for energizing the intermediate winding thereof, and to interrupt, at the contacts 615, the previously mentioned circuit for energizing the rotary magnet in order to arrest further operation of the wiper carriage of the finder F-1 at this time. Also, the electropolarized relay 610 completes, at the contacts 611 and 612, an obvious connection between the line conductors of the trunk line 203 seized by the line wipers of the wiper set 618 carried by the wiper carriage of the finder F-1 and the ring answer conductor 654 and the tip answer conductor 653 in cable #1, and, consequently, an operative connection between the subscriber substation T-1 and the headset at the first operator position OP-1.

Incident to operation of the change-over relay 630, and prior to the operation of the electropolarized relay 610, a circuit is completed for energizing the winding of the answer pilot relay 1340, this circuit extending from ground by way

of the winding of the answer pilot relay 1340, the release answer conductor 608 in cable #1, the contacts 676 and 632 and the resistor R4 to battery. When thus energized, the answer pilot relay 1340 operates to complete, at the contacts 1341, an obvious circuit for energizing the winding of the call signal relay 1140. When thus energized, the call signal relay 1140 operates shortly thereafter, the call signal relay 1140 being of the slow-to-operate type, to complete, at the contacts 1143, an obvious circuit for energizing the winding of the signal interrupter relay 1150. When thus energized, the signal interrupter relay 1150 operates shortly thereafter, this relay being of the slow-to-operate type, to complete, at the contacts 1152, an obvious circuit for energizing the winding of the signal interrupter relay 1160. When thus energized, the signal interrupter relay 1160 operates to complete, at the contacts 1162, an obvious holding circuit for energizing the winding thereof. Also, upon operating, the signal interrupter relay 1160 interrupts, at the armature 1162 and the back contact associated therewith, the previously mentioned circuit for energizing the winding of the call signal relay 1140, thereby to cause the latter relay to restore and interrupt, at the contacts 1143, the previously mentioned circuit for energizing the winding of the signal interrupter relay 1150, whereupon the latter relay restores. The sequential operation of the call signal relay 1140 and the signal interrupter relays 1150 and 1160, and the subsequent sequential restoration of the call signal relay 1140 and the signal interrupter relay 1150, cause tone current applied to the call tone conductor 1191 alternately to be connected to and disconnected from the talking repeater TR, whereupon a distinct zip-zip tone is produced in the headset at the first operator position OP-1, thereby to indicate to the operator therewith that the finder F-1 is searching for the trunk line over which the call is routed and that the call will arrive at the first operator position OP-1 shortly thereafter.

Also, upon operating, the answer pilot relay 1340 interrupts, at the armature 1343 and the back contact associated therewith, the previously traced circuit for energizing the winding of the start relay 1170; thereby to cause the latter relay to restore and interrupt, at the contacts 1171, the previously mentioned holding circuit for energizing the winding of the signal interrupter relay 1160, whereupon the latter relay restores. Further, the answer pilot relay 1340 completes, at the armature 1343 and the front contact associated therewith, a path for applying ground potential to the sequence control conductor 1304 extending to the sequence control circuit SCC, this circuit extending from ground by way of the contacts 1135, the conductor 1185, the contacts 1351, the armature 1343 and the front contact associated therewith and the contacts 1362 and 1393 to the sequence control conductor 1304. This application of ground potential to the sequence control conductor 1304 causes the sequence control circuit SCC to operate and select one of the sender links, such, for example, as the sender link SL-1. When the sender link SL-1 is thus selected, operation of both the link finder LF-1 and the sender selector SS-1 is initiated. The link finder LF-1 then operates to find cable #2 extending to the first link at the first operator position OP-1; and the sender selector SS-1 operates to find a cable extending

10 to an idle register sender, such, for example, as cable #4 extending to the register sender RS.

Continuing with the operation of the finder F-1 incident to the operation of the electropolarized relay 610, it is noted that, upon operating, the electropolarized relay 610 also completes, at the contacts 618, a multiple holding circuit for energizing the upper winding of the connect relay 670 in series with the winding of the talk relay 1130, this circuit extending from ground by way of the winding of the talk relay 1130, the hold conductor 605 in cable #1, the contacts 689, 618 and 679 and the upper winding of the connect relay 670 to battery. Also, the electropolarized relay 610 interrupts, at the contacts 617, the previously traced circuit for energizing the winding of the automatic start relay 600, thereby to cause the latter relay to restore. Upon restoring, the automatic start relay 600 interrupts, at the contacts 601, the previously traced original holding circuit for energizing the upper winding of the connect relay 670 in series with the winding of the talk relay 1130; and interrupts, at the contacts 603, the previously 20 mentioned circuit for energizing the winding of the start relay 660. However, the start relay 660 does not restore, at this time, due to a completed holding circuit for energizing the winding thereof, this circuit extending from ground by 25 way of the armature 1344 and back contact associated therewith, the start conductor 1302 in cable #1, the contacts 677 and the winding of the start relay 660 to battery. Also, the automatic start relay 600 interrupts, at the contacts 604, the previously traced circuit for energizing the upper winding of the automatic answer relay 605. However, the latter relay does not restore 30 at this time, due to the previously traced completed holding circuit for energizing the lower winding thereof.

Further, the electropolarized relay 610 completes, at the armature 613 and the front contact associated therewith, an obvious path for short-circuiting the upper winding thereof, thereby to 35 complete a path for applying ground potential to the control conductor of the seized trunk line 203 extending to the combined line and recording trunk circuit CLR-1, this path extending from ground by way of the contacts 634, the lower winding of the supervisory relay 650, the armature 613 and the front contact associated therewith, and the control wiper C1 of the wiper set 618 carried by the wiper carriage of the finder F-1 to the control conductor of the trunk line 203. This application of ground potential to the control conductor of the trunk line 203 causes the combined line and recording trunk circuit CLR-1 to operate, thereby to remove ground potential from the start conductor 313 extending 40 to the position distributor PD. When ground potential is removed from the start conductor 313, the previously traced original circuit for energizing the winding of the start relay 1210 in the position distributor PD is interrupted. Accordingly, at this time, the start relay 1210 restores in the event there are no other calls waiting to be answered at the switchboard, and remains operated in the event there are other calls to be answered at the switchboard.

Finally, the electropolarized relay 610 completes, at the contacts 619, an obvious path for applying ground potential to the guard conductor 1281 of the first link at the first operator position OP-1, thereby to initiate further operation of the first position link distributor LD-1.

at this time; whereupon the first position link distributor LD-1 operates to preselect the next idle link at the first operator position OP-1, in the manner previously explained. Further, it is noted that, when ground potential is applied to the guard conductor 1281 of the first link at the first operator position OP-1, ground potential is also applied to the guard conductor 1270 of the first operator position OP-1 due to the connection between the guard conductor 1281 and the guard conductor 1270, at the contacts 670' of the operated connect relay 670. The application of ground potential to the guard conductor 1270 in cable #1 initiates further operation of the position distributor PD; whereupon the position distributor PD operates to select the next idle operator position at the switchboard, in the manner previously explained.

In view of the above description of the operation of the finder F-1 of the first link at the first operator position OP-1 to seize a calling trunk line in the first one hundred line group accessible thereto, it will be readily appreciated that the finder F-1 will operate, in a similar manner, to seize a calling line in the second one hundred line group accessible thereto. In the last-mentioned case, the electropolarized relay 620, instead of the electropolarized relay 610, is operated in the finder F-1, whereupon the subsequent operation of the finder F-1 is the same as that previously explained.

At this time, an operative connection is completed between the calling subscriber substation T-1 and the operator position telephone equipment at the first operator position OP-1. The sender link SL-1 is operatively associated with the first link and with the register sender RS; and the operator digit keys DK are operatively associated with the sender link SL-1. Accordingly, at this time, the operator at the first operator position OP-1 communicates with the calling subscriber at the subscriber substation T-1 and is advised concerning the extension of the call; and the apparatus at the first operator position OP-1 is in readiness to extend the call by way of the toll first selector TFS-1 of the first link at the first operator position OP-1 in the event this is necessary.

Extension of a call from the switchboard in the central office to a distant exchange

Assuming that the incoming call from the calling subscriber substation T-1 is to be extended to the distant exchange DE-2, the operator at the first operator position OP-1 initiates the extension of the call by actuating the operator digit keys DK, as previously noted. More particularly, the operator digit keys DK are operated in order to cause the register sender RS to register a predetermined number of digits corresponding to the switch train route to the distant exchange DE-2. The register sender RS then operates, thereby to cause the sender link SL-1 to transmit the digits registered over cable #2 to the toll first selector TFS-1 of the first link at the first operator position OP-1. The toll first selector TFS-1 operates to seize an idle trunk line, such as the trunk line 402 extending to the toll switch train TST. The remaining digits transmitted to the toll switch train TST cause the toll switch train TST to seize an idle toll line, such as the toll line TL-2 extending between the central office CO and the distant exchange DE-2, the toll line TL-2 terminating at the operator position 410 in the distant exchange DE-2.

After all of the digits registered in the register sender RS have been transmitted by the sender link SL-1, the sender link SL-1 operates to cause battery potential to be connected to the control conductor 1553 in cable #2 and ground potential to be connected to the control conductor 1556 in cable #2 in the manner fully explained in the previously mentioned Crocker patent. The application of battery potential to the control conductor 1553 in cable #2 causes the toll switch train TST to operate and transmit ringing current over the toll line TL-2 in order to signal the operator at the operator position 410 in the distant exchange DE-2. The application of ground potential to the control conductor 1556 in cable #2 completes an obvious circuit for energizing the upper winding of the cut-through relay 680. When thus energized, the cut-through relay 680 operates to complete, at the contacts 685, an obvious holding circuit for energizing the lower winding thereof and to complete, at the contacts 681 and 682, a connection between the toll first selector TFS-1 and the operator position telephone equipment at the first operator position OP-1. More particularly, the line conductor 711 of the trunk extending to the toll first selector TFS-1 is connected by way of the contacts 681 and 671, the ring call conductor 655 in cable #1 and the armature 1322 and the back contact associated therewith to the ring conductor 1181 of the trunk circuit at the first operator position OP-1; and the line conductor 712 of the trunk extending to the toll first selector TFS-1 is connected by way of the contacts 682 and 673, the tip call conductor 656 in cable #1, and the armature 1321 and the back contact associated therewith to the tip conductor 1180 of the trunk circuit at the first operator position OP-1. Also, the cut-through relay 680 interrupts, at the contacts 689, the previously traced alternative holding circuit for energizing the upper winding of the connect relay 670 in series with the talk relay 1130, thereby to cause both the connect relay 670 and the talk relay 1130 to restore. Upon restoring, the connect relay 670 interrupts, at the contacts 672 and 674, the previously traced connection between the calling subscriber substation T-1 and the operator position telephone equipment at the first operator position OP-1; interrupts, at the contacts 671 and 673, the previously traced connection between the operator position telephone equipment at the first operator position OP-1 and the toll first selector TFS-1 of the first link at the first operator position; and completes, at the armatures 672 and 674 and the back contacts associated therewith a direct connection between the calling subscriber substation T-1 and the toll first selector TFS-1 in the first link at the first operator position OP-1, independently of the operator position telephone equipment at the first operator position OP-1. More particularly, at this time, the line conductor 711 of the trunk extending to the toll first selector TFS-1 is connected by way of the contacts 681, the armature 672 and the back contact associated therewith, and the contacts 611 to one of the line wipers of the wiper set 618 of the finder F-1; while the line conductor 712 of the trunk extending to the toll first selector TFS-1 is connected by way of the contacts 682, the armature 674 and the back contact associated therewith, and the contacts 612 to the other line wipers of the wiper set 618 of the finder F-1. Accordingly, at this time, an operative connection is completed between the

calling subscriber substation T-1 and the operator position 410 in the distant exchange DE-2.

Also, upon restoring, the connect relay 670 interrupts, at the contacts 670', the connection between the grounded guard conductor 1281 of the first link at the first operator position OP-1 and the guard conductor 1270 of the first operator position OP-1, thereby to mark the first operator position OP-1 as idle to the position distributor PD, in the manner previously explained. Also, upon operating, the cut-through relay 680 completes, at the contacts 681, an obvious multiple path for applying ground potential to the guard conductor 1281 of the first link at the first operator position OP-1; and interrupts, at the contacts 688, the previously traced holding circuit for energizing the lower winding of the automatic answer relay 605, thereby to cause the latter relay to restore. Upon restoring, the automatic answer relay 605 interrupts, at the contacts 607, the previously traced circuit for intermittently illuminating the link-busy lamp 603; and completes, at the contacts 608, an obvious multiple circuit for steadily illuminating the link-busy lamp 603, thereby to indicate to the operator at the first operator position OP-1 that the connection has been cut through to the toll first selector TFS-1 of the first link thereat.

Incident to operation of the cut-through relay 680, and prior to release of the connect relay 670, a circuit is completed for energizing the upper winding of the call pilot relay 1350, this circuit extending from ground by way of the lower winding of the cut-through relay 680, the contacts 685 and 669, the release call conductor 1355 in cable #1 and the upper winding of the call pilot relay 1350 to battery. When thus energized, the call pilot relay 1350 operates to interrupt, at the contacts 1351, the previously traced path for applying ground potential to the sequence control conductor 1304 extending to the sequence control circuit SCC; whereupon the sender link SL-1 and the register sender RS are released. Further, it is noted that when the connect relay 670 restores it interrupts, at the contacts 671, the previously traced holding circuit for energizing the winding of the start relay 660, thereby to cause the latter relay to restore; interrupts, at the contacts 676, the previously traced circuit for energizing the winding of the answer pilot relay 1340, thereby to cause the latter relay to restore; and interrupts, at the contacts 669, the previously traced circuit for energizing the upper winding of the call pilot relay 1350, thereby to cause the latter relay to restore. When the talk relay 1130, the answer pilot relay 1340 and the call pilot relay 1350 restore, the signal interrupter relay 1160 restores, thereby completely to release the operator position telephone equipment and the operator position relays at the first operator position OP-1.

At this time, an operative connection is completed between the calling subscriber substation T-1 in the central office CO and the operator position 410 in the distant exchange DE-2, whereupon the operator at the operator position 410 extends the call, in accordance with conventional practice.

Extension of other calls to and from the switchboard in the central office and supervision

In view of the above description of the mode of operation of the apparatus at the first operator position OP-1 at the switchboard in the central office CO to extend a call thereto from the calling

subscriber substation T-1 in the central office CO, it will be readily appreciated that the apparatus at the first operator position OP-1 at the switchboard in the central office CO is operative, in a similar manner, to extend other calls thereto. For example, a call may be extended from the operator position 210 in the distant exchange DE-1 to the first operator position OP-1 in the central office CO, by way of the toll line 10 TL-1 extending between the distant exchange DE-1 and the central office CO, the toll line circuit TCL-1, the trunk line 210 and the finder F-1 of the first link at the first operator position OP-1, the operation of the apparatus at the first operator position OP-1 at the switchboard in the central office CO, in the present example, being substantially identical to that previously explained.

In view of the above description of the mode of operation of the apparatus at the first operator position OP-1 at the switchboard in the central office CO to extend a call therefrom to the operator position 410 in the distant exchange DE-2, it will be readily appreciated that the apparatus at the first operator position OP-1 at the switchboard in the central office CO is operative, in a similar manner, to extend other calls thereto. For example, a call may be extended from the first operator position OP-1 at the switchboard in the central office CO to the subscriber substation T-2 in the central office CO by way of the toll first selector TFS-1 of the first link at the first operator position OP-1, the trunk line 403, the local switch train LST-2 25 and the subscriber line 406, the operation of the apparatus at the first operator position at the switchboard in the central office CO, in the present example, being substantially identical to that previously explained.

At this point, it is noted that the operator at the first operator position OP-1 at the switchboard in the central office CO has answer and release supervision of the calling line seized by the finder F-1 of the first link thereat by means of an arrangement including the answer lamp 602, the answer and release supervision arrangement being identical to that disclosed in the previously mentioned Crocker patent; also, the operator at the first operator position OP-1 at the switchboard in the central office CO has call and release supervision of the called line seized by the toll first selector TFS-1 of the first link thereat by means of an arrangement including the call lamp 601, the call and release supervision arrangement being identical to that disclosed in the previously mentioned Crocker patent.

Further, it is pointed out that the operator at the first operator position OP-1 at the switchboard in the central office CO may release a connection extended to her position instead of extending the connection therefrom, in the manner previously explained. For example, in the event a connection extended to the first operator position OP-1 at the switch board in the central office CO, by way of the first link thereat, is to be released prior to extension of the call from the first operator position OP-1, this may be accomplished by the operator at the first operator position OP-1 by operating the release answer key K-8 in the operator position key set. More particularly, when the release answer key K-8 is operated there is completed, at the contacts 1408 thereof, an obvious path for short-circuiting in multiple the winding of the answer pilot relay 1340, the upper winding of the change-over relay

630 and the lower winding of the automatic answer relay 605, thereby to cause the relays mentioned to restore. Upon restoring, the change-over relay 630 interrupts, at the contacts 634, the previously traced holding circuit for energizing the intermediate winding of the electropolarized relay 610, thereby to cause the latter relay to restore. Upon restoring, the electropolarized relay 610 interrupts, at the contacts 618, the previously traced holding circuit for energizing the upper winding of the connect relay 670 in series with the winding of the talk relay 1130, thereby to cause the latter relays to restore. Upon restoring, the answer pilot relay 1340 interrupts, at the armature 1344 and the front contact associated therewith, the previously traced holding circuit for energizing the winding of the start relay 660, thereby to cause the latter relay to restore. Upon restoring, the start relay 660 completes, at the contacts 661, an obvious circuit for energizing the release magnet, thereby to cause the wiper carriage of the finder F-1 to be released. Upon restoring, the automatic answer relay 605 interrupts, at the contacts 606, a further point in the holding circuit for energizing the lower winding thereof; and interrupts, at the contacts 607, the previously traced circuit for intermittently illuminating the link busy lamp 603. At this time, the finder F-1 of the first link at the first operator position at the switchboard is completely released when the operator thereat returns the release answer key K-8 to its normal position.

In the foregoing explanation of the mode of operation of the finder F-1 of the first link at the first operator position OP-1 at the switchboard, it was assumed that the operator thereat desired the connection to be switched through automatically from the calling line to the called line, exclusive of the first operator position OP-1, incident to the extension of the call from the first operator position OP-1. However, it may occur that the operator at the first operator position OP-1 desires the connection to be switched through automatically from the calling line to the called line, and including the first operator position OP-1, incident to the extension of the call from the first operator position OP-1. In this event, when the operator at the first operator position OP-1 answers the call on the first link thereat and determines that she desires the first operator position OP-1 to be included in the completed connection between the calling line and the called line, the operator at the first operator position OP-1 first operates the talk key K-1 of the finder F-1 of the first link prior to operation of the operator digit keys DK. At this time, when the talk key K-1 is operated, a further holding circuit is completed at the contacts of the talk key K-1 for energizing the upper winding of the connect relay 670 in series with the winding of the talk relay 1130, this circuit extending from ground by way of the winding of the talk relay 1130, the hold conductor 605 in cable #1, the contacts of the talk key K-1, the contacts 679 and the upper winding of the connect relay 670 to battery. Subsequently, when the cut-through relay 680 operates to interrupt, at the contacts 689, the previously traced alternative holding circuit for energizing the upper winding of the connect relay 670 in series with the winding of the talk relay 1130, the talk relay 1130 and the connect relay 670 remain in their operated positions due to the completed further holding circuit, including the contacts of the talk key K-1, for energizing the upper wind-

ing of the connect relay 670 in series with the winding of the talk relay 1130. Hence, at this time, the cut-through relay 680 completes, at the contacts 681 and 682, the previously traced connection between the toll first selector TFS-1 of the first link and the trunk circuit at the first operator position OP-1, the finder F-1 of the first link being connected to the trunk circuit at the first operator position OP-1, due to the operated connect relay 670 at this time. Accordingly, at this time, both the calling line and the called line are interconnected at the trunk circuit at the first operator position OP-1; and the operator thereat may communicate in either direction selectively or simultaneously over either the calling line or the called line. After the operator at the first operator position OP-1 satisfies herself concerning the routing of the connection, she may complete the previously traced direct connection between the finder F-1 and the toll first selector TFS-1 of the first link independently of the first operator position OP-1, and consequently the direct connection between the calling line and the called line, by restoring the talk key K-1 of the finder F-1, in the manner previously explained.

It is contemplated that the operator at the first operator position OP-1 will permit automatic switch-through of the links thereat, exclusive of the first operator position OP-1, primarily in connection with inward and through toll connections; and that, in conjunction with other connections, particularly C. L. R. connections, the operator at the first operator position OP-1 will cause automatic switch-through of the links thereat, including the first operator position OP-1, whereby the setting up of the connections is supervised.

In this connection, it is noted that the operator at the first operator position OP-1 at the switchboard may monitor a connection completed by way of the first link thereat merely by operating the monitor key K-2 of the finder F-1 of the first link thereat. The circuits completed, incident to the operation of the monitor key K-2 in order to complete the monitoring connection, are the same as those disclosed in the previously mentioned Crocker patent.

Further, it is pointed out that the release of the first link at the first operator position OP-1 at the switchboard is under the control of the operator thereat and that either the finder F-1 or the toll first selector TFS-1 may be selectively released. In order to effect the release of the first link at the first operator position OP-1 at the switchboard, the operator thereat first operates the talk key K-1 of the finder F-1 of the first link, thereby to complete an operative connection between the first link and the operator position key set, the circuits completed being fully described in the previously mentioned Crocker patent. At this time, the operator may release the finder F-1 and, consequently, the answer end of the first link by momentarily operating the release answer key K-8; or the operator may release the toll first selector TFS-1 and, consequently, the call end of the first link by momentarily operating the release call key K-12. Further, the operator may release substantially simultaneously both the finder F-1 and the toll first selector TFS-1 of the first link by momentarily operating the release answer and call key K-11.

Further, it is noted that, while the talk key K-1 of the finder F-1 of the first link at the

first operator position OP-1 at the switchboard is operated, the operator thereat may cut the answer end of the link off of the trunk circuit at the first operator position OP-1 by operating the cut-off answer key K-5; may cut the call end of the link off of the trunk circuit at the first operator position OP-1 by operating the cut-off call key K-15; may lock a defective calling toll line out of service by operating the transfer answer key K-6; may lock a defective called toll line out of service by operating the transfer call key K-14; may ring manually a calling line by operating the ring answer key K-7; may ring manually a called line by operating the ring call key K-13; and may transfer the supervision of all connections extended by way of the links at the first operator position OP-1 to the succeeding operator position by operating the position group key K-17. The detailed operation of the apparatus at the first operator position OP-1 at the switchboard in the central office CO, incident to the operation of the keys mentioned, is fully described in the previously mentioned Crocker patent.

Further, it is noted that the operator at the first operator position OP-1 at the switchboard may initiate a delayed call by first operating the delayed call key K-3 and the dial answer key K-9 in combination with the talk key K-1 of the finder F-1 of the first link at the first operator position OP-1, thereby to cause the finder F-1 to operate and seize a trunk extending to an idle toll delayed selector, such as the trunk 206 extending to the toll delayed selector TDS-1. The detailed operation of the apparatus, in order to cause the finder F-1 of the first link at the first operator position OP-1 to seize the trunk 206 extending to the toll delayed selector TDS-1, is fully described in the previously mentioned Crocker patent.

Further, it is noted that the operator at the first operator position OP-1 at the switchboard may initiate the operation of the finder of any selected idle one of the links at the first operator position OP-1 manually and independently of the operation of the position distributor PD, thereby to assist the other operators at the switchboard without waiting for the position distributor PD to extend a call automatically to the first operator position OP-1 at the switchboard. In order to accomplish this end, the operator at the first operator position OP-1 selects an idle link at her position, such as the link illustrated, and then operates the talk key K-1 thereof, thereby to cause operation of the connect relay 670, in the manner previously explained; whereupon an operative connection is completed between the finder F-1 of the first link and the operator position key set at the first operator position OP-1. The operator at the first operator position OP-1 then operates the emergency start key K-10, thereby to complete, at the contacts 1413 thereof, an alternative circuit for energizing the winding of the start relay 660, this circuit extending from ground by way of the contacts 1413 of the emergency start key K-10, the conductor 1449, the contacts 1363, the armature 1344 and the back contact associated therewith, the start conductor 1302 in cable #1, the contacts 677 and the winding of the start relay 660 to battery. When thus energized, the start relay 660 operates, thereby to effect operation of the finder F-1, in the manner previously explained; whereupon the finder F-1 operates to seize a calling line accessible thereto and to

extend a connection from the seized calling line to the first operator position OP-1 independently of the operation of the position distributor PD.

Finally, it is noted that interposition calls are answered independently of the position distributor PD. For example, a call answered at another operator position at the switchboard may be extended over the interposition transfer trunk 431 to the interposition transfer circuit ITC-1 accessible to the finders of the links at the first operator position OP-1. When a call is extended to the interposition transfer circuit ITC-1 this circuit operates, thereby to cause ground potential to be applied to the emergency start conductor 515 and extended therefrom by way of the contacts 1363 and 1344 to the start conductor 1302 in cable #1. Also, the interposition transfer circuit ITC-1 causes a signal lamp to be illuminated at the first operator position OP-1 in order to indicate to the operator thereat that an interposition call is waiting to be answered. In order to answer the interposition call, the operator at the first operator position OP-1 merely selects an idle link thereat, such, for example, as the link illustrated, and operates the talk key K-1 of the finder F-1 thereof. When the talk key K-1 of the finder F-1 of the first link at the first operator position OP-1 is operated at this time, the connect relay 670 operates, as previously explained, thereby to connect the grounded start conductor 1302 in cable #1 to the winding of the start relay 660. The start relay 660 then operates in order to initiate operation of the finder F-1 of the first link at the first operator position OP-1. At this point, it is noted that the trunk line 204 extending to the interposition transfer circuit ITC-1, together with the trunk line 206 extending to the toll delayed selector TDS-1, terminate in the first level of the contact bank associated with the wiper carriage of the finder F-1. Accordingly, the finder F-1 is operative to seize the trunk line 204 extending to the interposition transfer circuit ITC-1 in preference to other trunk lines, even though the operation of the finder F-1 of the first link at the first operator position OP-1 is initiated by the position distributor PD in response to the presence of a call on another trunk line at this time.

Operation of the apparatus to busy both a given operator position and the links thereto

Reconsidering now the operation of the finder F-1 of the first link at the first operator position OP-1 at the switchboard, it is pointed out that ground potential may be applied to the guard conductor 1281 of the first link at the first operator position OP-1, thereby to busy the first link, due to the operation of either the electropolarized relay 610 or 620 or the operation of the cut-through relay 680. More particularly, the electropolarized relays 610 and 620 and the cut-through relay 680 respectively complete, at the contacts 619, 629 and 687, obvious paths for applying ground potential to the guard conductor 1281 of the first link at the first operator position OP-1. Accordingly, the first link at the first operator position OP-1 is marked as busy to the first position link distributor LD-1 when either one of the electropolarized relays 610 or 620 or the cut-through relay 680 occupies its operated position.

Also, when the connect relay 670 in the finder F-1 of the first link at the first operator position OP-1 occupies its operated position, when

the first link is busy, ground potential appearing upon the guard conductor 1281 of the first link is connected, at the contacts 670', to the guard conductor 1270 of the first operator position OP-1, thereby marking the first operator position at the switchboard as busy to the position distributor PD.

In view of the above description of the mode of operation of the finder F-1 of the first link at the first operator position at the switchboard to mark the first link therat as busy to the first position link distributor LD-1 and to mark the first operator position OP-1 as busy to the position distributor PD, it will be understood that the finders of the intermediate and last links at the first operator position OP-1 are operative in a similar manner respectively to mark the intermediate and last links at the first operator position OP-1 as busy to the first position link distributor LD-1, and to mark the first operator position OP-1 as busy to the position distributor PD.

Further, it is noted that, upon operating, the electropolarized relays 610 and 620 and the cut-through relay 680 respectively prepare, at the contacts 610', 620' and 680', points in a multiple path in a series chain circuit for applying ground potential to the guard conductor 1270 of the first operator position OP-1 at the switchboard. Thus, it will be understood that, when each of the links at the first operator position OP-1 at the switchboard is busy, the above-mentioned series chain circuit is completed, thereby to apply ground potential to the guard conductor 1270 at the first operator position OP-1, in order to mark the first operator position at the switchboard as busy to the position distributor PD.

Also, it is pointed out that, when the operator at the first operator position OP-1 initiates a delayed call therefrom by operating the delay call key K-3, an obvious path is completed, at the contacts of the delayed call key K-3, for applying ground potential to the guard conductor 1270 of the first operator position OP-1, thereby to mark the first operator position OP-1 at the switchboard as busy to the position distributor PD in order to prevent a call from being routed by the position distributor PD to the first operator position at the switchboard while the operator thereat is initiating a delayed call therefrom. Further, it is noted that when the operator at the first operator position OP-1 operates the monitor key K-2 of the first link therat, a circuit is completed for energizing the winding of the monitor relay 1120, this circuit extending from ground by way of the contacts 692 of the monitor key K-2, the switching conductor 1357 in cable #1, the contacts 1334, the switching conductor 1182, the contacts 1134 and the winding of the monitor relay 1120 to battery. When thus energized, the monitor relay 1120 operates to interrupt at the armatures 1121, 1122 and 1123, and the back contacts associated therewith, the operative connection between the talking repeater TR and the operator headset in the operator position telephone equipment, and completes at the armatures 1121, 1122 and 1123, and the front contacts associated therewith, an obvious operative connection between the monitoring repeater MR and the operator headset. Further, the monitor relay 1120 completes, at the contacts 1124, an obvious path for applying ground potential to the guard conductor 1270 of the first operator position OP-1, thereby to mark

the first operator position OP-1 at the switchboard as busy to the position distributor PD.

Finally, it is noted that the operator at the first operator position OP-1 may busy the first operator position at the switchboard to the position distributor PD by operating the busy key K-18 at the first operator position OP-1, thereby to complete, at the contacts of the busy key K-18, an obvious path for applying ground potential to the guard conductor 1270 of the first operator position OP-1.

Conclusions

From the foregoing, it is apparent that a telephone system is provided, which comprises an automatic switchboard including a number of operator positions, each operator position being provided with a number of links individual thereto, and improved apparatus for automatically distributing both toll and trunk calls to selected idle ones of the operator positions in a predetermined order to be answered, and for automatically routing the calls to a selected operator position over selected idle ones of the links individual thereto in a predetermined order, thereby to insure that both toll and trunk calls are routed over idle links to idle operator positions, in an efficient manner.

While there has been described what is at present considered to be the preferred embodiment of the invention, it will be understood that various modifications may be made therein, and it is intended to cover in the appended claims all such modifications as fall within the true spirit and scope of the invention.

What is claimed is:

1. In a telephone system, a plurality of lines, an operator position, a group of links individually associated with said operator position, each of said links including an automatic answer switch and an automatic call switch, automatic means controlled when said operator position is idle for connecting an idle one of said links thereto and for selectively operating the answer switch of said one link to seize a calling one of said lines, thereby to extend the call on said calling line to said operator position to be answered, means responsive to the operation of the answer switch of said one link for rendering busy said one link, means controllable from said operator position for selectively operating the call switch of said one link to seize a called one of said lines, thereby to complete a connection between said calling line and said called line, means responsive to the operation of the call switch of said one link for rendering busy said one link and for disconnecting said one link from said operator position, and means controlled when a busy one of said links is connected to said operator position for rendering busy said operator position.

2. In a telephone system, a plurality of lines, an operator position, a group of links individually associated with said operator position, a group of signals associated with said operator position and individually corresponding to said links, each of said links including an automatic answer switch and an automatic call switch, automatic means controlled when said operator position is idle for connecting an idle one of said links thereto and for operating the one of said signals corresponding to said one link and for selectively operating the answer switch of said one link to seize a calling one of said lines, thereby to extend the call on said calling line to said operator position to be answered, means responsive to the operation of the answer switch

of said one link for rendering busy said one link, means controllable from said operator position for selectively operating the call switch of said one link to seize a called one of said lines, thereby to complete a connection between said calling line and said called line, means responsive to the operation of the call switch of said one link for rendering busy said one link and for disconnecting said one link from said operator position, and means controlled when a busy one of said links is connected to said operator position for rendering busy said operator position.

3. In a telephone system, a plurality of lines, an operator position, a group of links individually associated with said operator position, a group of signals associated with said operator position and individually corresponding to said links, each of said links including an automatic answer switch and an automatic call switch, automatic means controlled when said operator position is idle for connecting an idle one of said links thereto and for operating the one of said signals corresponding to said one link in a first manner and for selectively operating the answer switch of said one link to seize a calling one of said lines, thereby to extend the call on said calling line to said operator position to be answered, means responsive to the operation of the answer switch of said one link for rendering busy said one link, means controllable from said operator position for selectively operating the call switch of said one link to seize a called one of said lines, thereby to complete a connection between said calling line and said called line, means responsive to the operation of the call switch of said one link for rendering busy said one link and for arresting operation of said one signal in said first manner and for operating said one signal in a second manner while said one link is busy, means for disconnecting said one link from said operator position, and means controlled when a busy one of said links is connected to said operator position for rendering busy said operator position.

4. In a telephone system, a plurality of lines, an operator position, a group of links associated with said operator position, each of said links including an answer switch and a call switch, automatic means controlled when said operator position is idle for connecting an idle one of said links thereto and for operating the answer switch of said one link to seize a calling one of said lines, thereby to extend the call on said calling line to said operator position to be answered, means responsive to the operation of the answer switch of said one link for rendering busy said one link, means controllable from said operator position for operating the call switch of said one link to seize a called one of said lines, thereby to complete a connection between said calling line and said called line, means responsive to the operation of the call switch of said one link for rendering busy said one link, means for disconnecting said one link from said operator position, means controllable from said operator position for selectively connecting busy ones of said links to said operator position, thereby to supervise the connections, and means controlled when a busy one of said links is connected to said operator position for rendering busy said operator position.

5. In a telephone system, a plurality of lines, an operator position, a group of links individually associated with said operator position, each of said links including an automatic answer

switch and an automatic call switch, automatic means controlled when said operator position is idle for connecting an idle one of said links thereto and for selectively operating the answer switch of said one link to seize a calling one of said lines, thereby to extend the call on said calling line to said operator position to be answered, means responsive to the operation of the answer switch of said one link for rendering busy said one link, means controllable from said operator position for selectively operating the call switch of said one link to seize a called one of said lines, thereby to complete a connection between said calling line and said called line, means responsive to the operation of the call switch of said one link for rendering busy said one link, means for disconnecting said one link from said operator position, means controlled when any one of said links is connected to said operator position for preventing other of said links from being connected to said operator position, and means controlled when a busy one of said links is connected to said operator position for rendering busy said operator position.

6. In a telephone system, a plurality of lines, an operator position, a group of links associated with said operator position, each of said links including an answer switch and a call switch, automatic means controlled when said operator position is idle for connecting an idle one of said links thereto and for operating the answer switch of said one link to seize a calling one of said lines, thereby to extend the call on said calling line to said operator position to be answered, means responsive to the operation of the answer switch of said one link for rendering busy said one link, means controllable from said operator position for operating the call switch of said one link to seize a called one of said lines, thereby to complete a connection between said calling line and said called line, means responsive to the operation of the call switch of said one link for rendering busy said one link, normally effective means controlled in response to the operation of the call switch of said one link for disconnecting said one link from said operator position, means controllable from said operator position for rendering ineffective said last-mentioned means, and means controlled when a busy one of said links is connected to said operator position for rendering busy said operator position.

7. In a telephone system, a plurality of lines, an operator position, a group of links associated with said operator position, each of said links including an answer switch and a call switch, automatic means controlled when said operator position is idle for connecting an idle one of said links thereto and for operating the answer switch of said one link to seize a calling one of said lines, thereby to extend the call on said calling line to said operator position to be answered, means responsive to the operation of the answer switch of said one link for rendering busy said one link, means controllable from said operator position for operating the call switch of said one link to seize a called one of said lines, thereby to complete a connection between said calling line and said called line, means responsive to the operation of the call switch of said one link for rendering busy said one link, means controllable from said operator position for operating the call switch of said one link to seize a called one of said lines, thereby to complete a connection between said calling line and said called line, means controlled when a busy one of said links is connected to said operator position for rendering busy said operator position, means controllable from said operator position for selectively establishing monitoring connections between said operator

position and busy ones of said links, thereby to supervise the connections, and additional means controlled when a monitoring connection is established between said operator position and a busy one of said links for rendering busy said operator position.

8. In a telephone system, a plurality of lines, an operator position, a group of links associated with said operator position, each of said links including an answer switch and a call switch, automatic means controlled when said operator position is idle for connecting an idle one of said links thereto and for operating the answer switch of said one link to seize a calling one of said lines, thereby to extend the call on said calling line to said operator position to be answered, means responsive to the operation of the answer switch of said one link for rendering busy said one link, means controllable from said operator position for operating the call switch of said one link to seize a called one of said lines, thereby to complete a connection between said calling line and said called line, means responsive to the operation of the call switch of said one link for rendering busy said one link, means for disconnecting said one link from said operator position, means controlled when a busy one of said links is connected to said operator position for rendering busy said operator position, and additional means controlled when all of said links are rendered busy for rendering busy said operator position.

9. In a telephone system, a plurality of lines, an operator position, a group of links individually associated with said operator position, each of said links including an automatic answer switch and an automatic call switch, automatic distributor means for selecting idle ones of said links in a predetermined order and controlled when said operator position is idle for connecting a selected one of said links thereto and for selectively operating the answer switch of said one link to seize a calling one of said lines, thereby to extend the call on said calling line to said operator position to be answered, means responsive to the operation of the answer switch of said one link for rendering busy said one link, means controllable from said operator position for selectively operating the call switch of said one link to seize a called one of said lines, thereby to complete a connection between said calling line and said called line, means responsive to the operation of the call switch of said one link for rendering busy said one link, means for disconnecting said one link from said operator position, and means controlled when a busy one of said links is connected to said operator position for rendering busy said operator position.

10. In a telephone system, a plurality of lines, a number of operator positions, a number of groups of links individually associated with said operator positions, each of said links including an answer switch and a call switch, means for selecting the ones of said groups of links associated with idle ones of said operator positions in a predetermined order, means for selecting idle ones of the links in said groups of links in a predetermined order, means for connecting a selected one of said links in a selected one of said groups of links to the associated one of said operator positions and for operating the answer switch of said one link to seize a calling one of said lines, thereby to extend the call on said calling line to said one operator position to be answered, means responsive to the operation of

the answer switch of said one link for rendering busy said one link, means controllable from said one operator position for operating the call switch of said one link to seize a called one of said lines, thereby to complete a connection between said calling line and said called line, means responsive to the operation of the call switch of said one link for rendering busy said one link, means for disconnecting said one link from said operator position, and means controlled when a busy link in any one of said groups of links is connected to the associated one of said operator positions for rendering busy said one operator position.

11. In a telephone system, a plurality of lines, an operator position, a group of links associated with said operator position, automatic means for selecting an idle one of said links, distributor means responsive to the presence of a call on any one of said lines and controlled when said operator position is idle for routing the call on said calling line over said selected link to said operator position to be answered, additional means controllable from said operator position for selecting an idle one of said links, additional means controllable from said operator position for routing a call on a calling one of said lines over said selected link to said operator position to be answered, means controlled when a call is routed over any one of said links for rendering busy said one link, and means controlled when a call is routed to said operator position to be answered for rendering busy said operator position.

12. In a telephone system, a plurality of lines, an operator position, a group of links associated with said operator position, automatic distributor means responsive to the presence of a call on any one of said lines and controlled when said operator position is idle for connecting an idle one of said links to said operator position and to said calling line, thereby to extend the call on said calling line to said operator position to be answered, additional means controllable from said operator position for connecting an idle one of said links to said operator position and to a calling one of said lines, thereby to extend the call on said calling line to said operator position to be answered, means controlled when said one link is connected to said calling line for rendering busy said one link, means for disconnecting said one link from said operator position, and means controlled when a busy one of said links is connected to said operator position for rendering busy said operator position.

13. In a telephone system, a plurality of lines, an operator position, a group of links associated with said operator position, automatic distributor means responsive to the presence of a call on any one of said lines and controlled when said operator position is idle for transmitting a seizure signal to said operator position and for connecting an idle one of said links to said operator position and to said calling line, thereby to extend the call on said calling line to said operator position to be answered, additional means controllable from said operator position for connecting an idle one of said links to said operator position and to a calling one of said lines, thereby to extend the call on said calling line to said operator position to be answered, means controlled when said one link is connected to said calling line for rendering busy said one link, means for disconnecting said one link from said operator position, and means controlled when a

busy one of said links is connected to said operator position for rendering busy said operator position.

14. In a telephone system, a plurality of lines, an operator position, a group of links associated with said operator position, automatic distributor means for selecting idle ones of said links in a predetermined order and responsive to the presence of a call on any one of said lines and controlled when said operator position is idle for connecting a selected one of said links to said operator position and to said calling line, thereby to extend the call on said calling line to said operator position to be answered, additional means controllable from said operator position for connecting an idle one of said links to said operator position and to a calling one of said lines, thereby to extend the call on said calling line to said operator position to be answered, means controlled when said one link is connected to said calling line for rendering busy said one link, means for disconnecting said one link from said operator position, and means controlled when a busy one of said links is connected to said operator position for rendering busy said operator position.

15. In a telephone system, a plurality of lines, an operator position, a group of links associated with said operator position, automatic distributor means for selecting idle ones of said links in a predetermined order and controlled when said operator position is idle for connecting a selected one of said links to said operator position and to a calling one of said lines, thereby to extend the call on said calling line to said operator position to be answered, additional means including a manually operable device at said operator position for connecting an idle one of said links to said operator position and to a calling one of said lines, thereby to extend the call on said calling line to said operator position to be answered, means controlled when said one link is connected to said calling line for rendering busy said one link, means for disconnecting said one link from said operator position, and means controlled when a busy one of said links is connected to said operator position for rendering busy said operator position.

16. In a telephone system, a plurality of lines, a number of operator positions, a number of groups of links individually associated with said operator positions, means for selecting the ones of said groups of links associated with idle ones of said operator positions in a predetermined order, means for selecting idle ones of the links in said groups of links in a predetermined order, means for connecting a selected one of said links in a selected one of said groups of links to the associated one of said operator positions and to a calling one of said lines, thereby to extend the call on said calling line to said one operator position to be answered, additional means controllable from any one of said operator positions for connecting an idle one of the links in the associated one of said groups of links thereto and to a calling one of said lines, thereby to extend the call on said calling line to said one operator position to be answered, means controlled when said one link is connected to said calling line for rendering busy said one link, means for disconnecting said one link from said one operator position, and means controlled when a busy link in any one of said groups of links is connected to the associated one of said operator positions for rendering busy said one operator position.

17. In a telephone system, a plurality of lines, an operator position, a group of links associated with said operator position, automatic distributor means responsive to the presence of a call on any one of said lines and controlled when said operator position is idle for connecting an idle one of said links to said operator position and to said calling line, thereby to extend the call on said calling line to said operator position to be answered, additional means controllable from said operator position for connecting an idle one of said links to said operator position and to a calling one of said lines, thereby to extend the call on said calling line to said operator position to be answered, means controlled when said one link is connected to said calling line for rendering busy said one link, means controllable from said operator position for connecting said one link to a called one of said lines, thereby to complete a connection between said calling line and said called line, means controlled when said one link is connected to said called line for rendering busy said one link, means for disconnecting said one link from said operator position, and means controlled when a busy one of said links is connected to said operator position for rendering busy said operator position.

18. In a telephone system, a plurality of lines, an operator position, a group of links associated with said operator position, each of said links including an answer switch and a call switch, automatic means controlled when said operator position is idle for connecting an idle one of said links thereto and for operating the answer switch of said one link to seize a calling one of said lines, thereby to extend the call on said calling line to said operator position to be answered, additional means controllable from said operator position for connecting an idle one of said links thereto and for operating the answer switch of said one link to seize a calling one of said lines, thereby to extend the call on said calling line to said operator position to be answered, means responsive to the operation of the answer switch of said one link for rendering busy said one link, means controllable from said operator position for operating the call switch of said one link to seize a called one of said lines, thereby to complete a connection between said calling line and said called line, means responsive to the operation of the call switch of said one link for rendering busy said one link, means for disconnecting said one link from said operator position, and means controlled when a busy one of said links is connected to said operator position for rendering busy said operator position.

19. In a telephone system, a plurality of lines, an operator position, a group of links associated with said operator position, each of said links including an answer switch and a call switch, automatic means controlled when said operator position is idle for connecting an idle one of said links thereto and for operating the answer switch of said one link to seize a calling one of said lines, thereby to extend the call on said calling line to said operator position to be answered, means responsive to the operation of the answer switch of said one link for rendering busy said one link, means including a register sender associated with said operator position and controllable therefrom for operating the call switch of said one link to seize a called one of said lines, thereby to complete a connection between said calling line and said called line, means responsive to the operation of the call switch of said one link for render-

ing busy said one link, means controlled by said register sender for disconnecting said one link from said operator position, and means controlled when a busy one of said links is connected to said operator position for rendering busy said operator position.

20. In a telephone system, a plurality of lines, an operator position, a group of links associated with said operator position, each of said links including an answer switch and a call switch, automatic means controlled when said operator position is idle for connecting an idle one of said links thereto and for operating the answer switch of said one link to seize a calling one of said lines, thereby to extend the call on said calling line to said operator position to be answered,

means responsive to the operation of the answer switch of said one link for rendering busy said one link, means including a sender key set at said operator position for operating the call switch of said one link to seize a called one of said lines, thereby to complete a connection between said calling line and said called line, means responsive to the operation of the call switch of said one link for rendering busy said one link, means controlled by said sender key set for disconnecting said one link from said operator position, and means controlled when a busy one of said links is connected to said operator position for rendering busy said operator position.

THOMAS F. CROCKER.
